WORTHINGTON COMPANY, OF HARTFORD, CONNECTICUT, A CORPORATION
OF CONNECTICUT.

HORSE-COLLAR.

1,103,973.

Specification of Letters Patent.

Patented July 21, 1914.

Application filed April 1, 1913. Serial No. 758,150.

To all whom it may concern:

Be it known that I, ROBERT G. LILLEY, a citizen of the United States, residing at Hartford, in the county of Hartford and State of Connecticut, have invented a new and useful Improvement in Horse-Collars, of which the following is a specification.

This invention relates to the construction of a horse collar for a draft harness, or what 10 is commonly known as a hames collar.

The object of the invention is to so put the parts together that with a saving of material and a reduction in the cost of labor, an inexpensive collar is produced which has 15 the neat and attractive appearance and the efficiency and durability of a high class collar.

Collars of this class have a fore-wale or small roll and an after-wale or body, with 20 creases or grooves between the roll and the body for receiving the hames. The fore-wale comprises a leather covering suitably stuffed with straw or the like filling and the after-wale comprises a back piece of leather 25 or other material and a lining of leather or other fabric which are commonly stuffed with straw to form the pad. Certain types of these collars, inside of the lining and forming a softer cushion for bearing against 30 the neck and shoulders of the horse, have a facing which is commonly made of ticking or similar fabric and is usually stuffed with hair.

In attaining the object of this invention, 35 the back piece and lining of the body are so attached to the covering of the front roll and to each other, and the facing is so attached, that without the employment of what is known as a shoulder piece, the seams and 40 raw edges of the parts are covered and protected and yet the facing can be removed at any time when it becomes worn and a new one substituted without ripping the collar to pieces. To accomplish this the front edges 45 of the back piece and the lining of the body are inserted and stitched between the back edges of the covering for the front roll, and the outer edge of the lining is permanently stitched to the back some distance in from 50 the outer edge of the back, and the facing has its inner edge stitched to the lining and its outer edge attached to the underside of the back by hand stitching or a lacing which passes through the facing and the back be- 55 tween the outer edge of the back and the

line of stitching which joins the outer edge of the lining to the back, whereby the back covers and protects the raw outer edge of the lining and also the raw outer edge of the facing, and yet allows the facing to be readily removed by cutting the lacing without interfering with the stitching which secures the lining and the back. 60

Figure 1 of the accompanying drawings shows a front view of a collar which is constructed according to this invention. Fig. 2 is a view looking at the back of this collar. Fig. 3 shows an edge view of the collar. Fig. 4 shows on a larger scale a transverse section on the plane indicated by the dotted line 4-4 on Fig. 2. 70

The fore-wale or small roll of this collar is as usual made up of a strip of leather 1 stuffed with straw 2 to give it the proper shape and stiffness. The front edges of the 75 back 3, which is made of leather, and the lining 4, which is made of leather, are inserted between the edges of the leather which forms the covering for the small roll and these edges are secured by a row of 80 stitches 5 which pass through the edges of the roll cover, the back and the lining. Around the collar outside of these and in the hames-grooves is placed a band of leather 6 and this band is held in place by a row of 85 stitches 7 which pass through it and also through the edges of the roll cover, back and lining. This strip attached in this way protects the main stitches which fasten the parts together and tends to stiffen the joint and 90 also keep the roll and body well separated to insure wide "hames-room." 90

The outer edge of the lining is secured to the inside of the back some distance in from the outer edge of the back by a row 95 of stitches 8. The space between the back and the lining is usually stuffed with straw 9 to give the necessary shape and provide the required padding.

The facing 10 is preferably made of what 100 is commonly known as ticking, but may be made of other sufficiently firm fabric. The inner edge of the facing is attached by a row of stitching 11 to the inside of the covering of the small roll at the upper or withers end 12 of the collar, and to the lining along the inside of the collar and at the throat or gullet end 13 of the collar. The outer edge of the facing is attached to 105 the inside of the back some distance in from 110

the edge by a line of coarse stitching or lacing 14. This forms the outer edge of the back into a skirt 15 which projects over and covers the outer edges of the lining and the facing. The space between the facing and the lining is stuffed with hair 16 to provide the desired cushion.

A collar constructed in this manner has the neat and efficient appearance of a shoulered collar, although it has no shoulder piece applied to the outside of the back. With this formation there is no chance for the seam to wear and open in the hames-room and thus permit the collar during use 10 to pull apart beneath the hames. This construction saves material, for it is unnecessary to provide a shoulder piece over the back and the back is so attached to the roll that not only is it unlikely to give way at 15 that point, but it permits the seam between the lining and the back to be covered and protected, and it also covers and protects the seam between the back and the facing, yet it permits the facing to be removed and the collar to be refaced when necessary 20 without disturbing the seams which fasten together the back and the lining. This collar is not only made up from a minimum amount of material and with a minimum 25 expenditure of labor, but while cheaply constructed has the appearance of a high class 30

collar without the necessity of using what is called the shoulder piece to cover the back and outer edges of the lining and facing.

The invention claimed is:

A collar having a roll formed of a leather cover and a filling material, a body formed of a back, a lining and a filling material, the front edges of the lining and the back being inserted and stitched between the edges of the roll cover, and the outer edge of the lining being stitched to the inner surface at a distance in from the outer edge of the back so as to leave a protecting skirt, a facing comprising a fabric and filling material, 45 said facing fabric at its inner edge being stitched directly to the lining and having its outer edge extending inwardly and lying naturally against the inner surface of said skirt, and a lacing passing through and 50 through the facing and back a distance in from the outer edge of the skirt, whereby the outer edge of the facing will be concealed beneath the skirt and yet be attached independently of the lining so as to 55 allow the facing to be unlaced from the back without disturbing the stitches which secure the lining to the back.
